UNITED STATES PATENT OFFICE.

FRANK A. HARVEY, OF MINNEAPOLIS, MINNESOTA.

BOXING-GLOVE.

SPECIFICATION forming part of Letters Patent No. 570,092, dated October 27, 1896.

Application filed May 22, 1896. Serial No. 592,554. (No model.)

To all whom it may concern:

Be it known that I, FRANK A. HARVEY, a citizen of the United States, residing at Minneapolis, in the county of Hennepin and State 5 of Minnesota, have invented certain new and useful Improvements in Pneumatic Boxing-Gloves; and I do hereby declare the following to be a full, clear, and exact description of the invention, such as will enable others 10 skilled in the art to which it appertains to make and use the same.

My invention has for its object to provide a pneumatic boxing-glove.

To this end the invention consists of the 15 novel construction hereinafter described, and defined in the claim.

The invention is illustrated in the accompanying drawings, wherein, like letters referring to like parts throughout the several 20 views—

Figure 1 is a side elevation of the left-hand glove. Fig. 2 is a longitudinal central section of the right-hand glove. Fig. 3 is a perspective view of the left-hand glove, looking 25 at the palm side of the same. Fig. 4 is a view, partly in perspective and partly in cross-section, showing the outer end portion of one of the gloves. Fig. 5 is a detail in longitudinal section, with some parts broken away, showing 30 the relation of the neck or nipple portion of the bladder to the adjacent parts of its cover. Fig. 6 is a detail somewhat similar to Fig. 5, but with the bladder left in elevation and pulled apart from the cover; and Fig. 7 35 is a cross-section through the right-hand glove in the plane of the thumb-piece.

a represents the glove proper, or part of the boxing-glove which fits over the hand, of the ordinary or any suitable construction. *a'* 40 represents the cushion-back, made of the proper shape and fullness and joining the glove proper at the proper points to coöperate with the back and the tip of the glove proper to form a cover for an inside expansible bladder *b*. The said bladder *b* is of a 45 proper shape to fit the cover for the same and of the proper size to expand the cover to the proper tension when the bladder is filled with air to the desired pressure. Otherwise 50 stated, the bladder *b* is made of rubber or other expansible material of such size that, if outside the cover, it would expand to much

larger size than the cover when filled with air to the same pressure as when used inside the cover. This bladder *b* is provided with a 55 thumb-piece, which is adapted to fit the recess between the back of the thumb-cell and the thumb-section of the cushion-back *a'*, as best shown in Fig. 7. The said bladder *b* is provided with the nipple *b'*, fitted with the 60 check-valve *b*² at the neck of the bladder. When collapsed, the bladder may be inserted into the cover through an opening or mouth-slit *a*² on the inside of the glove, of sufficient 65 size to permit the fingers of the hand to be inserted therein for positioning the thumb-piece and the nipple of the bladder. After the bladder has been inserted into the cover through the mouth-slit *a*² the nipple *b'* is pushed outward through a small hole or perforation *a*³ in the cushion-back *a'* near the 70 wrist part of the glove, so as to occupy the position shown in Fig. 5. The bladder is then inflated with air to the desired pressure and the nipple *b'* is placed under an elastic keeper 75 *a*⁴, fixed to the back of the wrist portion of the glove, so as to assume the position shown in Figs. 1, 2, and 3. The glove is then ready for use. With the construction above described it must be obvious that all the striking-surfaces of the glove will be cushioned 80 by the air-charged bladder. The tension of this cushion may of course be varied at will by simply varying the air-pressure in the bladder. 85

A pneumatic boxing-glove of this character is a great improvement over the ordinary padded glove. The cushion is substantially the same at all points of the striking-surface, the glove is comparatively light and is perfectly flexible, thereby rendering the same 90 comfortable and easy to the hand. The difference in the weight for any given desired cushion is a very great improvement. The glove has all the above-noted advantages 95 without any material disadvantages as compared with the padded glove. The valve *b*² in the bladder is so located that when the glove is in use the said valve will be for the most part surrounded by the air within the 100 bladder, and the only part thereof not air-cushioned will be at a point never used for striking purposes.

It will be understood that the details of the

construction shown might be changed without departing from the spirit of my invention.

What I claim, and desire to secure by Letters Patent of the United States, is as follows:

5 The combination with the glove proper, constructed with the cushion-back a^1 , coöperating as a bladder-cover, provided with the mouth-slit a^2 opening into the interior of the glove, the keeper a^4 , formed on the back of
10 the same, and the nipple-passage a^3 opening

outward of said keeper a^4 , of the bladder b having the nipple b' and the check-valve b^2 , substantially as and for the purpose set forth.

In testimony whereof I affix my signature in presence of two witnesses.

FRANK A. HARVEY.
